UNITED STATES PATENT OFFICE.

DAVID J. HAUSS, OF AURORA, INDIANA.

MUSIC-PLAYER.

1,192,194.

Specification of Letters Patent. Patented July 25, 1916.

Application filed October 23, 1909. Serial No. 524,119.

To all whom it may concern:

Be it known that I, DAVID J. HAUSS, a citizen of the United States, residing at Aurora, in the county of Dearborn and State of Indiana, have invented certain new and useful Improvements in Music-Players, of which the following is a specification.

My invention relates to improvements in electrically actuated music players. One of its objects is to provide improved means to feed the music sheet, to regulate the speed with which the sheet is fed, to stop and start the feed, and to feed the sheet backward at an increased rate.

Another object is to provide improved mechanism to conveniently control the various movements of the sheet.

It further consists in certain details of form, combination and arrangement, all of which will be more fully set forth in the description of the accompanying drawings in which:

Figure 1 is a front elevation of a piano with my improvements attached thereto. Fig. 2 is a diagram of the controller mechanism and electrical connections to said controller and motor. Fig. 3 is a side elevation of the controller. Fig. 4 is a detail of a modification of Fig. 3. Fig. 5 is a sectional detail of the rewinding clutch mechanism. Fig. 6 is a similar view of a modification. Fig. 7 is a sectional detail of the clutch shifting mechanism.

In the accompanying drawings A represents the piano casing.

B represents an electric motor.

C represents a shaft which is clutched to and adapted to drive the sheet feeding roll C' from which the sheet is being fed during the act of producing the music.

D represents a shaft which carries and is adapted to drive the roll D² which receives the sheet during the act of producing the music.

D' represents a shaft which is mounted concentrically with the shaft D and is driven slowly from the motor B by means of a worm b on the motor shaft, a worm wheel b' on the shaft b² and thence by beveled gear b³ on shaft b² and beveled gear b⁴ on shaft D'. Two spur gears d d' are mounted side by side on the adjacent ends of shafts D D' and motion is transmitted from gear d' to gear d by means of a pinion d² having a face wide enough to mesh with both gears

d and d'. The pinion d² is carried on pivoted frame d³, and is adapted to be shifted into and out of engagement with gears d d' by means of a lever d⁴ having inclined projections d⁵ to shift said frame. Said lever 60 also preferably at the same time serves to open and close a switch d⁶ controlling the music key circuits.

The opposite end of the motor shaft carries a friction gear c which is engaged by a 65 friction gear c' on a shaft c² journaled in frame d³. Shaft c² carries a sprocket-wheel c³ which by means of a sprocket chain c⁴ and sprocket wheel c⁵ on shaft C tends to drive shaft C in a direction opposite to that 70 which it would be driven by the rotation of shaft D. When the gears d d' d² are in mesh the shaft D rotates the music rolls C' D² in the direction to feed the sheet from roll C' to roll D², and friction gear c' is out 75 of engagement with friction gear c. When the gear d² is thrown out of mesh with gears d d' the friction gear c' is shifted into engagement with friction gear c and serves to rotate the music rolls at an increased speed 80 to transfer the sheet from roll D² to roll C'.

In the modification Fig. 7 the motor is provided with a pinion C⁷ in place of a friction gear and a spur gear c⁸ carried by frame d³ is shifted into mesh with pinion c⁷, and 85 in turn drives spur gear c⁹ on shaft C to rewind the sheet on roll C'. If desired a duplicate set of gears d d' d² may be employed to drive shaft C to rewind the sheet.

The motor is preferably of the direct current type comprising a magnetic field energized by a field coil H, an armature h, a commutator h', and a plurality of contact brushes h² h³. 90

The motor is controlled by means of a controller preferably comprising two sections J J'. The section J is pivotally supported by means of a grooved collar j of insulating material which rests between the forked arms of a bracket k which is rigidly supported upon the controller block or base K. The section J' is telescopically adjustable within the bore of section J and is splined and prevented from turning within the bore of section J or being completely withdrawn 100 therefrom by a screw j'. The forward or projecting end of section J' is downwardly turned to facilitate holding and manipulation of the controller, said section being preferably insulated from section J. 105

L represent buttons arranged upon the controller block K concentrically about the center L', and upon opposite sides thereof. The block K is of insulating material and 5 has pivoted thereto at the center L' a cross bar or switch lever M the opposite ends of which are adapted to contact with diametrically opposite buttons L. Sections of resistance wire l serve to connect in series adjacent buttons L upon opposite sides of the block K. The bar M has also connected thereto and projecting at substantially right angles a forked arm M', the forked end of which engages opposite sides of a sleeve m 10 of insulating material carried by the section J of the controller.

N N' represent contact plates carried by the block K and adapted to be alternately or selectively engaged by the contacts or 15 brushes n n' carried by the controller section J. A spring n² serves to normally hold the controller in position to make contact between the plate N and brush n.

A line O connects the lower button L of 20 the right hand series with the contact brush h² of the motor. A line P connects the upper button L of the left hand series with the brushes n n'. A line R connects the plate N with lead screw r of the motor, 25 which is in turn connected by line r' with one end of the field coil H. Plate N' is connected by line S with the lead screw T of the motor which in turn is connected by line t with the opposite end of the coil H, and 30 by line t' with the contact brush h³ of the motor.

U U' represent the line wires.

When not in operation the controller section J' is telescoped within section J so as 35 to be out of the way beneath the key board. When in operation the section J' is drawn forward so that its forward end projects slightly beyond the key board. The sheet rolls being adjusted to position, and the main line switch V closed to supply current to the motor, and brush n and plate N being in contact, the motor will start to rotate and slowly feed the sheet from roll C' to roll D². The speed of the motor can be 40 varied within the limits required by moving the controller lever J' to the right or left, a movement to the right increasing and to the left decreasing the motor speed. When it is desired to stop the motor the controller lever J' is turned upon its axis to break the contact at n, N, and to make contact at n' N' which serves to convert the armature from a 45 motor to a generator with the resistance l in circuit and a separately excited field, which acts as a brake upon the armature and stops 50 its rotation instantly. After the sheet has been fed from roll C' to D² the lever d⁴ is shifted to throw gear d² out of mesh with gear d, whereupon the friction gears c' 55 drive the roll C' at increased speed in the 60 65

reverse direction to return the sheet to roll C'.

In the modification Fig. 4 the plates 2, 3 corresponding to the plates N N' of Fig. 3 are located above and below the controller 70 lever 4, and to stop the motor the controller lever is lifted vertically to break contact between the brush 5 and plate 2, and to make contact between the brush 6 and plate 3.

The mechanism herein illustrated and described is capable of considerable modification without departing from the principle of my invention.

Having described my invention, what I claim is:

1. In a music player, a pair of sheet feeding rolls, an electric motor having a driving member at each end of its shaft, gear trains driven from opposite ends of the motor shaft to feed the sheet from one roll to the other in either direction, mechanism to reciprocally engage one of said sheet feeding rolls in driving relation with said motor and disconnect the opposite sheet feeding roll from driving relation with said motor, and controlling means to stop, start, and vary the speed of said motor.

2. A music player driving mechanism comprising a pair of sheet feeding rolls, an electric motor having a slow speed driving gear at one end of its shaft and a higher speed driving gear at the opposite end of its shaft, gear trains leading from said gears at opposite ends of the motor shaft to drive the respective sheet feeding rolls in opposite directions at relatively different speeds, and a controlling lever to alternately connect one of said gear trains in driving relation with its sheet roll and to disconnect the other gear train from driving relation with its sheet roll.

3. A music player driving mechanism comprising a pair of sheet feeding rolls, an electric motor having a slow speed driving gear at one end of its shaft and a higher speed driving gear at the opposite end of its shaft, gear trains leading from said gears at opposite ends of the motor shaft to drive the respective sheet feeding rolls in opposite directions at relatively different speeds, a reciprocally operated lever to alternately connect one of said gear trains in driving relation with its sheet roll and to disconnect the other gear train from driving relation with its sheet roll, and motor controlling means to stop, start, and vary the speed of said motor.

4. A music player driving mechanism comprising a pair of sheet feeding rolls, an electric motor having a worm gear mounted at one end of its shaft and a higher speed driving gear mounted at the opposite end of the motor shaft, gear trains leading from said gears at opposite ends of the motor shaft to drive the respective sheet

feeding rolls in opposite directions at relatively different speeds, and mechanism to reciprocally engage one of said feeding rolls in driving relation with said motor and to disconnect the opposite feeding roll from driving relation with said motor.

In testimony whereof I have affixed my signature in presence of two witnesses.

DAVID J. HAUSS.
